ANTICREEP ANCHORAGE MEANS FOR
TIRE BOOTS

George A. Stanzel, Des Moines, Iowa

Application May 5, 1934, Serial No. 724,056

9 Claims. (Cl. 152—26)

This invention relates to improvements in anti-creep anchorage means for tire boots of the type which is in the form of small metal body members adapted to be secured to the tire boot so as 5 to be placed between the boot and the tire casing when the boot is in position, to prevent slippage of the boot relative to the casing, the object of my invention being to provide a simple, durable and inexpensive anti-creep device which may 10 be formed from sheet metal by the stamping process, and adapted to be secured to the outer surface of the boot in such a manner that the projecting prongs of the device will enter the fabric of the casing when pressure is applied to 15 the boot upon the inner tube being inflated.

A further object of my invention is to provide an anti-creep device for tire boots, having improved means for more securely fastening the device to the boot and at the same time increase 20 the clinging effect.

A further object is to provide in an anti-creep device of the type having laterally projecting prongs, an improved means whereby the prongs may more readily enter the fabric and be more 25 rigidly secured thereto with less cutting effect on the cords of the fabric.

My invention consists in the construction, arrangement and combination of the various parts of the device, whereby the objects contemplated 30 are attained, as hereinafter more fully set forth, pointed out in my claims, and illustrated in the accompanying drawing, in which:

Figure 1 is a perspective view of my improved anti-creep device.

Figure 2 is an enlarged detail sectional view showing the manner in which the device is applied to a tire boot and casing.

Figure 3 is a perspective view of the tire boot showing the manner in which my improved device are applied thereto.

Figure 4 is a transverse sectional view of a portion of the tire tread, together with the boot, showing the manner in which the anti-creep devices are applied.

Figure 5 is an enlarged sectional view showing the manner in which one of the barbed prongs of the anti-creep device enters the tire boot fabric.

Figure 6 is a perspective view of a slightly modified form of my device.

My improved anti-creep device comprises preferably a pair of disc shaped body members 10, one of which is superimposed upon the other, the discs being connected by means of a rivet 11, the 55 adjoining faces of the discs being slightly con-

vexed so as to permit one disk to rotate freely upon the other. The edge of each disc is provided with a series of outwardly and laterally projecting prongs 12, each of the prongs having its outer end pointed and provided with a barbed portion 13, as clearly illustrated in Figure 1.

The anti-creep device is applied to the tire boot 14, which is of ordinary construction, by means of the rivet 11, in the manner illustrated in Figure 2, the devices being riveted to the outer 10 surface of the tire boot near the inner edge of the bevelled portion of the boot. Any desired number of these anti-creep devices may be applied, although I preferably use either four or eight. As the anti-creep device is applied to the 15 boot the prongs 12 of the inner disk 10 are forced into the rubberized fabric until the outer surface of the disk engages the outer surface of the tire boot. The pointed end of the prongs will have a tendency to work themselves in between the 20 cords 15, causing the adjoining cords to be sprung apart, some of the cords entering above the barb 13, as illustrated in Figure 5. The tendency of the cords to assume their original position will cause the cords to enter the space above the 25 member 13.

In applying the boot to the inner surface of the casing 15a the boot is simply placed in position over the ruptured portion of the casing in the usual manner, after which the inner tube is 30 applied and inflated. The pressure created by the inner tube will force the prongs of the outer disc 10 into the rubberized fabric of the casing 15a. By pivotally connecting the inner disc 10 to the outer disc it will be seen that the disc is 35 perfectly free to rotate to permit the pointed end of the prongs to enter between the cords of the casing rather than to sever them, the barbed portion 13 of the said prongs tending to lock the prongs in position and to thereby more rigidly 40 secure the boot to the casing.

Pivoting the inner disc to the outer disc also greatly decreases the tendency of the barbs to mutilate the casing, due to the continuous stretching and movement of the casing relative to the 45 boot as the reinforced portion of the casing is moved into and out of engagement with the ground surface.

In Figure 6 I have illustrated a slightly modified form in which a single disc 16 is pivotally connected to the outer surface of the boot by means of a suitable rivet 17, the disc 16 being similar to the disc 10 and provided with similar barbed prongs 18, the latter construction being used with cheaper and lighter casings.

Another advantage in my construction lies in the fact that the barbed portion of the prongs, after they have been forced into the fabric, will securely hold the boot in place in the casing 5 even after the casing has become deflated, thus preventing the boot from loosening and moving in the casing, and preventing the prongs from mutilating the inner surface of the casing in case the tire is operated a short distance while being deflated, which condition usually occurs each time a 10 puncture takes place.

It will, therefore, be seen that I have provided a simple, durable and inexpensive anti-creep device for tire boots which may be easily and 15 quickly applied to the boot and, when so applied, is firmly supported against being torn loose, and also provides efficient means for securing the boot to the casing to prevent creeping wherein the tendency of mutilation of the boot is materially decreased, thus providing means whereby 20 the boot may be easily and quickly applied without the use of cement and other adhesive compositions.

I claim as my invention:

25 1. An anti-creep anchorage means for tire boots comprising a disc having barbed prongs projecting laterally from its edge, a second disc similar to the first disc, means pivotally connecting said discs together, the prongs of one disc being adapted to be imbedded in said boot, with the prongs of the opposite disc imbedded in the casing in which the boot is mounted.

30 2. An anti-creep anchorage means for tire boots comprising a pair of discs, means pivotally connecting said discs together, the outer surface of each disc being provided with laterally projecting prongs for the purpose stated.

35 3. An anti-creep anchorage means for tire boots comprising a pair of discs, means pivotally connecting said discs together, the adjoining surfaces of said discs being slightly convexed, the outer surface of each disc being provided with laterally projecting prongs for the purpose stated.

40 4. An anti-creep anchorage means for tire boots comprising a pair of discs, means pivotally connecting said discs together, the adjoining surfaces of said discs being slightly convexed, the outer surface of each disc being provided with

laterally projecting prongs, each of the prongs being barbed for the purpose stated.

5 5. The combination of a tire casing, a boot within said casing, a series of anti-creep devices secured to the outer surface of said boot and to the inner surface of said tire casing, said anti-creep devices comprising a pair of disc shaped body members, means pivotally connecting said body members together, each of said discs having a series of laterally projecting barbed prongs, the 10 prongs of one disc being imbedded in the boot and the prongs of the other disc being imbedded in the tire casing.

6. An anti-creep anchorage means for tire boots comprising a disc having barbed prongs projecting laterally from its edge; a second disc similar to the first disc; and means pivotally connecting said discs together, the prongs of one disc being adapted to be imbedded in said boot, with the prongs of the opposite disc imbedded in the casing 20 in which the boot is mounted.

7. An anti-creep anchorage means for tire boots comprising a disc having barbed prongs projecting laterally from its edge, means for pivotally connecting the disc to the outer surface of a tire boot, 25 said prongs being adapted to be imbedded in the tire casing when a boot is applied therein, the disc being permitted to rotate slightly relative to the boot to permit the barbs of the prongs to more freely enter between the cords of the casing 30 to which the boot is applied.

8. The combination of a tire boot, a disc having barbed prongs projecting laterally from its edge, means pivotally securing said disc to said boot, the barbs of said prongs projecting in a common 35 circumferential direction whereby the disc may be slightly rotated about its pivot as pressure is applied to said boot to permit the barbs of said prongs to more readily enter between the cords of the casing to which the boot is applied, for the 40 purpose stated.

9. An anti-creep anchorage means for tire boots comprising a disc having its edge provided with laterally projecting prongs, each having a barb, 45 all of said barbs projecting in a common circumferential direction, and means for pivotally connecting said disc to a tire boot.

GEORGE A. STANZEL.
